CLIP-ON FLASHLIGHT

Bronislaw Zapolski, Princeton, N.J., assignor to Herbert J. Ashe, ½ The H. J. Ashe Company, Inc., South Norwalk, Conn.

Filed Sept. 23, 1968, Ser. No. 13,660

Term of patent 14 years

Int. Cl. D26—04

U.S. Cl. D48—24

FIG. 1

FIG. 4

FIG. 2

FIG. 3

FIG. 5

FIG. 6

FIG. 7

FIGURE 1 is a top plan view of my design for a clip-on flashlight;

FIGURE 2 is a front elevational view thereof;

FIGURE 3 is a right side elevational view thereof;

FIGURE 4 is a left side elevational view thereof;

FIGURE 5 is a bottom plan view thereof;

FIGURE 6 is a rear elevational view thereof, and

FIGURE 7 is a perspective view showing the front, one side, and the top of my new design for a clip-on flashlight.

I claim:

The ornamental design for a clip-on flashlight, substantially as shown.
